UNITED STATES PATENT OFFICE.

JAMES R. ROSSETTER, OF KNOXVILLE, TENNESSEE.

PLOW.

1,032,298.

Specification of Letters Patent.

Patented July 9, 1912.

Application filed March 4, 1911. Serial No. 612,249.

To all whom it may concern:

Be it known that I, JAMES R. ROSSETTER, a citizen of the United States, residing at Knoxville, in the county of Knox and State 5 of Tennessee, have invented certain new and useful Improvements in Plows, of which the following is a specification.

One object of this invention is to construct the parts of a plow in such manner that they 10 may be used interchangeably and thereby reduce the number of parts or extras the dealer must carry in order to meet the demands of the plow users. The interchangeability of the parts also reduces the number 15 of patterns the manufacturer must employ and consequently lessens the cost of production.

There is a well-defined and growing demand for a plow with interchangeable 20 shares and my present invention seeks to meet that demand by providing a plow which will prove efficient whether the cutter is integral with or separate from the share and whether the share is or is not formed with a gunnel, the several parts in 25 every instance being secured together in such manner as to preserve the shape of the plow and reduce the liability of breakage.

A further object of the invention is to 30 provide a moldboard in which the liability of a destroying fracture is reduced to a minimum.

Another object of the invention is to so 35 secure the end of the beam to the saddle or standard as to overcome the tendency of the same to work loose under the strain to which it is subjected.

Other incidental objects of the invention 40 will appear as the description of the same proceeds and at the end of the description the novel features of the invention will be distinctly pointed out in the claims.

One form of my invention is illustrated 45 in the accompanying drawings, in which—

Figure 1 is a side view showing the parts assembled, the share having a gunnel and the cutter being removable. Fig. 2 is a similar view showing a share having the cutter integral therewith but formed without a gunnel. Fig. 3 is a plan view of the 50 standard with the beam in section. Fig. 4 is a horizontal section on the line 4—4 of Fig. 2. Fig. 5 is a perspective view of the standard or saddle. Fig. 6 is a side view 55 of the standard. Fig. 7 is an elevation of

the standard partly broken away looking at the side opposite that seen in Fig. 6 and indicating the end of the beam in dotted lines. Fig. 8 is a detail view of the end of the beam. Figs. 9 and 10 are elevations of the 60 landside looking at the opposite sides of the same. Figs. 11 and 12 are detail perspective views of the false gunnel. Fig. 13 is a detail rear elevation of the moldboard.

The standard, frog or saddle 1 is provided 65 on its moldboard side, or face, at its upper end, with a recess or seat 2 to receive a rearwardly projecting lip or lug at the upper end of the cutter as is usual to retain the cutter in position. On the landside face or 70 member of the standard or saddle is a horizontal rib 3 which curves downwardly at its front end and terminates in a shoulder 4. The under surface of this rib is beveled or arranged at an angle to the landside face of 75 the saddle and its rear end 5 is inclined rearwardly from its lower to its upper edge and is also beveled inwardly and forwardly. Below the rib a recess or groove 6 is formed 80 in the landside face of the saddle, said groove being of an oval or pear shape with its smaller or tapered end adjacent the extreme front end or point of the saddle. The walls of the groove merge into the face of 85 the saddle and the groove extends rearwardly and slightly upwardly from the front extremity of the saddle to a point about midway the landside face thereof, the depth of the groove gradually increasing toward its rear wider end. Below the rear 90 end of the groove on the lower edge of the saddle is a lateral lug 8 having its front and rear ends slightly converging outwardly and also upwardly while the lower edge of the saddle is cut away so that the portions 95 in front and rear of the lug occupy slightly different horizontal planes, an approximately vertical shoulder 9 being thereby provided on the lower edge of the saddle. The gunnel 10 and the landside 11 meet over 100 this lug 8 and are so shaped that when they engage they will be interlocked between the lug and the rib 3 in such a manner as to effectually preserve the curve of the plow.

The lower corner of the gunnel is cut 105 away so as to fit against the front end and over the upper side of the lug as shown, the edge of the gunnel being beveled to correspond to the inclination of the front end of the lug. The rear end of the gunnel extends 110

beyond the front end of the rib 3 and its upper edge 12 is inclined at the proper angle to fit snugly against the shoulder 4. The cutter will rest against the front edge of the 5 saddle, whether formed integral with the share and gunnel or separate therefrom, and if a detachable cutter be employed it will be provided with a lip adapted to engage recesses in the share and the moldboard to 10 hold its lower end in position. In molding shares with gunnels a "swell" is very apt to form on the gunnel, and, heretofore, this swell has destroyed the curve of the plow and frequently prevented the use of the 15 gunnel. By providing the recess 6, however, I am enabled to use all these gunnels as the "swell" will be accommodated in the recess and the gunnel may then be fitted close to the landside face of the standard or 20 saddle so that the outer faces of the share, gunnel and landside will be flush and follow the desired line.

The landside 11 has its front lower corner cut away, as shown at 13, to fit against the 25 rear end and over the upper side of the lug 8, the rear wall of said cut away portion being beveled inwardly and rearwardly to correspond to the inclination of the rear end of the lug. Rising from the said cut-away 30 portion or corner, the front edge of the landside presents a vertical beveled shoulder 14 adapted to engage the intermediate portion of the rear edge of the gunnel. An inclined shoulder 15 being provided at the upper end 35 of said vertical shoulder to engage the rear portion of the upper inclined edge of the gunnel. The shoulder 15 extends to the rib 3 and the upper edge 16 of the landside curves upwardly and rearwardly so as to 40 follow the outline of the lower side of the rib, being beveled to fit closely against the same. The gunnel is thus held by both the saddle and the landside so that any tendency of the gunnel to swing upwardly is positively resisted and effectually overcome 45 while at the same time the end of the landside is held against vertical movement and has an extended engagement with the saddle to aid in resisting the thrust thereon.

50 About midway its length, the upper edge of the landside is projected upwardly and beveled inwardly and forwardly to provide the offset or shoulder 17 adapted to engage the shoulder 5 on the rear edge of the saddle 55 at the end of the rib 3. On its inner face, along its lower edge, the landside is constructed with a rib or flange 18 which terminates flush with the rear wall of the cut-away portion 13 so as to engage the shoulder 9 of the saddle. This flange expands laterally toward its rear end and constitutes a wide runner for the landside while the square engagement of its front end and the landside with the shoulder 9 and lug 8 on 60 the saddle creates a wide bearing between 65

the landside and the saddle to aid in holding the share to its work and resisting the strain of opening the earth.

The arrangement and beveled construction of the several shoulders presented by 70 the saddle, the lug 8, the gunnel, and the landside brings the several parts into such assembled relation as to preserve the curve of the plow, the outer faces of all the parts lying flush, as shown. As the share is bolted to the moldboard face of the standard, a single bolt 19 will suffice to secure the landside to the saddle, the peculiar interlocking engagement of the landside with the gunnel and the saddle preventing movement of the 80 landside around the bolt.

If it be desired to use a share which is not formed with a gunnel, the same saddle and the same landside may be employed. In this instance, I provide a filler or false gunnel 85 20 to extend between the shoulder 21 on the share and the front end of the landside and preserve the continuity of the landside surface of the plow. This false gunnel is an irregular shaped plate of such thickness 90 that, when it is placed against the saddle or standard, its outer face will be flush with the outer faces of the share point and the landside. On its inner face, this plate is provided with a wing 22 which projects beyond the rear end of the plate and corresponds in shape to the recess 6 in which it fits snugly. In the projecting end of the wing is a countersunk opening 23 through which and a registering opening in the 100 standard is inserted a bolt 24 to secure the plate to the standard. The front end of the plate presents a vertical shoulder 25 adapted to engage the shoulder 21 on the share, and from the upper end of said shoulder 25 the edge of the plate extends upwardly and rearwardly on a curve 26 corresponding to the rear curved edge of the cutter portion of the share. From the upper 105 end of said curved portion, the edge of the plate extends downwardly and rearwardly, as at 27, to fit against the shoulder 4 on the saddle or standard and the shoulder 15 on the front end of the landside, while the rear end of the plate presents the vertical shoulder 28, to engage the front end of the landside, and the notch or cut-away corner 29 to engage the front end of the lug 8 on the saddle. It will be seen at once that the front 110 end of the landside overlaps the wing 22 and thereby aids in holding the plate in position and, as the edges of the plate are beveled to correspond to the bevel of the abutting or engaging surfaces, the several parts 115 will be interlocked so as to be firmly retained in their proper relative positions. It may be noted, further, that the provision of this false gunnel strengthens the plow at a point which has heretofore been a source of 120 weakness as it eliminates the offset previously 125 130

employed on the point of the share to engage the saddle and the end of the landside and substitutes therefore a vertical shoulder bearing against a similar shoulder on the 5 point of the share.

It will be noticed that the recess 6 and the wing engaging the same are of such shape that they gradually merge, toward their front ends, into the member with which 10 they are formed. The recess can thus be carried close to the extremity of the saddle without decreasing the quantity of metal therein to such an extent as to dangerously weaken it. Furthermore, there is no obstacle 15 to the location of the shoulder 4 and the lug 8 at the proper points to hold the gunnel and the landside in their relative positions while a sufficiently extended bearing face is provided to prevent dislocation of the false 20 gunnel.

On the inner end of the landside member of the saddle, at the upper end thereof, is a short rib or elongated lug 30 having a convex surface and also curved from end to end 25 to fit in the concave groove 31 in the side of the beam 32, the end of which is curved downwardly and secured to the lower portion of the landside member of the saddle. The lower extremity of the beam is constructed with a lug 33 on its rear edge 30 through which a bolt hole 34 extends, said bolt hole being countersunk at one end to fit over a conical boss 35 formed on the inner face of the landside member of the saddle around 35 the opening which receives the bolt 19 while a notch or open-ended slot 36 is formed in the front side of the beam at the lower end thereof to engage a lug 37 on the saddle adjacent the bolt hole which receives the bolt 40 24, the slot being of sufficient length to embrace the sides of said bolt, so that the nut mounted thereon may be turned home against the foot or lower end of the beam. It will thus be seen that the forward bolt 45 which fastens the beam to the saddle does not pass through the landside but is seated in the saddle under the landside and secures the false gunnel when the same is used. The liability of the bolt becoming loose and 50 releasing the landside is thus overcome and the number of bolts necessary to secure the parts is reduced, the rear corner of the beam being secured by the same bolt which secures the landside. It will also be seen that the 55 beam is held to the saddle in such a manner that the bolts are relieved of all hauling or draft strain and serve merely to hold the beam against the saddle. As a result of the described arrangement, the beam will not 60 work loose under hard usage.

In the process of chilling moldboards the metal has a tendency to crack as it contracts, and it is also rendered more liable to break when in use, and in order to overcome such 65 defects I form on the back of the mold-

board button-like protuberances 38 which are arranged in irregular or staggered relation and extend over practically the entire rear surface of the moldboard, except a part thereof at the front which rests against the 70 standard or saddle to which the moldboard is secured, and thereby cause the castings to shrink more uniformly, so that the percentage of fractures during the chilling process becomes so small as to be negligible 75 while liability to breakage in practical use is reduced to a minimum, for the reason that at the start a fracture will encounter a protuberance, which is very hard to break through, and must take a zigzag course with 80 consequent resistance. Moreover in the chilling process the protuberances do not always come out soft but each has a matted formation which prevents the fracture going through one, and it is either arrested or 85 compelled to encounter great resistance by taking a zigzag course.

It will be readily seen from the foregoing description taken in connection with the accompanying drawings, that I have provided 90 a plow, the parts of which are easily molded and fitted together and which, when together, will be interlocked, so that the plow will retain its original shape and not lose its "suck" and "gather." Furthermore, the 95 interchangeability of the parts is distinctly advantageous, as a dealer having a few parts may meet the demand for a wide variety of plows. For instance, with three points, the false gunnel, landside and saddle 100 herein shown and described, together with a standard and landside disclosed in my application filed simultaneously herewith, any one of four distinct plows may be provided. 105

Having described my invention, I claim as new and desire to secure by Letters Patent:

1. A plow saddle having a rib on its landside member extending between its front 110 and rear edges and a lateral lug at the lower extremity of said member intermediate the ends thereof, in combination with a gunnel and a landside fitting between said rib and said lug, the rear end of the gunnel and the front end of the landside meeting over and being supported by the lug. 115

2. A plow saddle having a rib on its landside member extending continuously between the front and rear edges thereof, a lateral landside and gunnel supporting lug at the lower edge of said member, and a recess in said member between said lug and said rib extending to the front extremity of the saddle. 120

3. A plow saddle having a lateral lug at the lower edge of its landside member and a recess in said member above said lug and extending beyond both ends of the same. 130

4. A plow saddle having a landside mem-

- ber provided in its outer face with a depression extending longitudinally of said member and lying entirely inward beyond the plane of the face of the member, the rear end of said depression being wider and deeper than the front end thereof.
5. A plow saddle provided at the lower edge of its landside member with a lateral lug, the said lower edge of the saddle occupying different planes in front and in rear of said lug.
10. The combination of a plow saddle having a boss on the inner face of its landside member, and a lug on said face in advance of said boss, a beam having its lower end provided with a countersunk opening to engage said boss and a slot to engage said lug, and fastening devices inserted through the saddle and the beam, one of said devices 20 passing through the said slot and another of said devices passing through said boss and the countersunk opening engaging the same.
15. A moldboard having on the back thereof button-like protuberances arranged in irregular or staggered relation in all directions throughout practically its entire rear surface whereby a straight line of appreciable length drawn across the moldboard in any direction will intercept two protuberances.
25. A chilled moldboard having small unchilled protuberances on the back thereof arranged in irregular or staggered relation in all directions and dotting practically its entire rear surface whereby a straight line of appreciable length drawn across the moldboard in any direction will intercept two protuberances.
30. The combination with a plow saddle having a lateral lug on the lower edge of its landside member, of a gunnel, and a landside, said gunnel and landside engaging said lug and interlocking above the lug.
35. The combination with a plow saddle having a vertical shoulder on the lower edge of its landside member, of a landside provided on its inner face with a longitudinal rib extending under the saddle and having an abrupt front end bearing against the 40 vertical shoulder on the lower edge of the saddle.
45. The combination with a plow saddle having a longitudinal rib on its landside member, and a lug on the lower edge of said member, of a gunnel engaging the front end of said lug and bearing against said rib, and a landside engaging the rear end of said lug and also bearing against said rib, the gunnel and landside interlocking between the lug and the rib.
50. The combination with a plow saddle having a longitudinal rib on its landside member, and a lug on the lower edge of said member, of a gunnel engaging the front end of said lug and bearing against said rib, and a landside engaging the rear end of said lug and also bearing against said rib, the gunnel and landside interlocking between the lug and the rib.
55. The combination with a plow saddle having a longitudinal rib on its landside member, and a lug on the lower edge of said member, of a gunnel engaging the front end of said lug and bearing against said rib, and a landside engaging the rear end of said lug and also bearing against said rib, the gunnel and landside interlocking between the lug and the rib.
60. The combination with a plow saddle having a longitudinal rib on its landside member, and a lug on the lower edge of said member, of a gunnel engaging the front end of said lug and bearing against said rib, and a landside engaging the rear end of said lug and also bearing against said rib, the gunnel and landside interlocking between the lug and the rib.
65. The combination with a plow saddle provided on its landside member with a longitudinal rib having its front end curved downwardly and terminating in a shoulder disposed at an angle to the front edge of the saddle, of a gunnel having its upper edge engaging said shoulder and extending rearwardly beyond the same, and a landside having its upper edge bearing against the under side of the rib and its front end engaging the rear end of the gunnel and extending over the upper edge of the same.
70. The combination with a plow saddle having a longitudinal rib on its landside member, a lateral lug at the lower edge of said member, and a longitudinal groove between said shoulder and lug, a share fitting on the point of the saddle, a landside engaging said lug and said longitudinal rib, and a gunnel fitted to said groove and interlocking with the share, the landside, the lateral lug and the longitudinal rib.
75. The combination with a plow saddle having a longitudinal rib on its landside member, a lateral lug at the lower edge of said member, and a longitudinal groove between said shoulder and lug, a share fitting on the point of the saddle, a landside engaging said lug and said longitudinal rib, and a gunnel fitted to said groove and interlocking with the share, the landside, the lateral lug and the longitudinal rib.
80. The combination with a plow saddle having a longitudinal rib on its landside member, a lateral lug at the lower edge of said member, and a longitudinal groove between said shoulder and lug, a share fitting on the point of the saddle, a landside engaging said lug and said longitudinal rib, and a gunnel fitted to said groove and interlocking with the share, the landside, the lateral lug and the longitudinal rib.
85. The combination with a plow saddle having a longitudinal rib on its landside member, a lateral lug at the lower edge of said member, and a longitudinal groove between said shoulder and lug, a share fitting on the point of the saddle, a landside engaging said lug and said longitudinal rib, and a gunnel provided on its inner side with a wing fitting in said recess, the rear end of the wing engaging under the front end of the landside and the edges of the gunnel interlocking with the landside, the share, and the rib and lug on the saddle.
90. The combination with a plow saddle having a longitudinal rib on its landside member, a lateral lug at the lower edge of said member, and a longitudinal groove between said shoulder and lug, a share fitting on the point of the saddle, a landside engaging said lug and said longitudinal rib, and a gunnel provided on its inner side with a wing fitting in said recess, the rear end of the wing engaging under the front end of the landside and the edges of the gunnel interlocking with the landside, the share, and the rib and lug on the saddle.
95. In testimony whereof I affix my signature, in presence of two witnesses.
